(57) CLAIM

The ornamental design for a bed, as shown and described.

DESCRIPTION

FIG. 1 is a front, right and top perspective view of a bed, showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, right and top perspective view of the bed, shown in an open configuration;

FIG. 9 is an enlarged view of detail 9 in FIG. 1; and,

FIG. 10 is an enlarged view of detail 10 in FIG. 8.

The broken lines shown in the drawings are included for the purpose of illustrating portions of the bed that form no part of the claimed design. In addition, the dot-dash broken lines in FIGS. 1 and 8-10 depict the boundaries of the enlargements that form no part of the claimed design.

1 Claim, 10 Drawing Sheets
